UNITED STATES PATENT OFFICE

WILLIAM A. RINGLER, OF PHILADELPHIA, PENNSYLVANIA, ASSIGNOR TO INDIVIDUAL DRINKING CUP COMPANY, INC., OF EASTON, PENNSYLVANIA, A CORPORATION OF PENNSYLVANIA

DRINKING CUP

Original application filed April 18, 1924, Serial No. 707,355. Divided and this application filed July 13, 1928. Serial No. 292,470.

This invention relates to improvements in drinking cups of the class which are formed of paper or like material and adapted for individual use, the present application being a division of an application Serial No. 707,355 filed by me April 18, 1924.

An object of the present invention is to provide an improved cup of the class referred to which will permit of the nesting of the 10 cups together in a stack in a dispensing device and that can be readily gripped and withdrawn singly from the dispenser.

Another object of the invention is to provide an improved cup of the collapsible type 15 possessing the characteristic referred to, which will be strongly reinforced, and which will be of a satisfactory efficient nature and inexpensive to manufacture.

The invention, with other objects and advantages thereof, and the particular construction, combination and arrangement of parts comprising the same, will be understood from the hereinafter contained detail description when considered in connection 25 with the accompanying drawings forming part hereof and illustrating one embodiment of the invention.

In the drawings:

Figure 1 is an elevation taken from one 30 side of a cup constructed in accordance with the present invention.

Fig. 2 is a similar view taken from the opposite side of the cup.

Fig. 3 is a top plan view.

Fig. 4 is a longitudinal section on the line 35 4-4 of Figure 1.

Fig. 5 shows the blank from which the cup is formed.

Fig. 6 is a front elevation, with parts 40 broken away, of a dispensing device with a stack of the cups therein.

Fig. 7 is a longitudinal section on the line 45 7-7 of Figure 6.

Fig. 8 is a transverse section on the line 50 8-8 of Figure 6.

Referring to a detail description of the particular embodiment of the invention illustrated in the drawings, the cup shown is of flat or collapsible form constructed from 55 a single blank A of paper or other material

suitable for the purpose, the blank A being shown in Figure 5. The blank is adapted to be folded transversely on the line 1 and thence folded longitudinally on the converging lines 2, 3, to provide downwardly tapering front and back walls 4, 5, of the cup joined at their lower ends and each having integral side flap extensions 6, 7, also joined at their lower ends. The flap extensions 6 of the back wall 5 are shown of general rectangular shape slightly enlarged adjoining the flap extensions 7, the latter flap extensions being shown of general triangular outline and of greater width than the flap extensions 6, said flap extensions, as shown in Figure 2, being bent over and secured by adhesive to the back wall 5, the flap extensions 6 being pasted to the back wall 5, and the flap extensions 7 overlapping the flap extensions 6 and being secured to the back wall 5 as well as to the flap 60 extensions 6. The side flap extensions 6, 7, formed integral with the front and back walls 4, 5, of the cup extending throughout the full length of said front and back walls, as shown, and folded and secured, as set forth, 65 afford efficient sealing connections at the sides of the cup, said flap extensions also serving to reinforce and brace the cup structure in an efficient way, the flap extensions 7 broadening out toward the base of the cup and extending well toward the central part thereof. 70

At either end the blank A has portions which are folded outwardly back upon the front wall 5 and back wall 4 of the cup providing transversely extending reinforcing 75 flaps 8, 9, at the top part of the cup. These flaps 8, 9, are preferably secured by adhesive to the front and back walls 4, 5, the flap 8 overlapping and being secured to the side flap extensions 7, as shown, as well as to the back wall 5 of the cup. 80

The cup, as shown, has downwardly converging side edges and is adapted to be nested with similar cups in a stack and held within a dispensing device. 85

The cup is provided at its bottom part with a handle portion 10 providing for the easy, ready withdrawal of the cups singly from a stack of the cups within a dispensing device, said handle portion being formed by a trans- 90

verse fold of a bottom section of the cup body extending laterally to one side thereof as shown in Figure 4. In the particular construction shown the fold that forms the handle portion 10 is made on the line 11, see Figure 5. The handle fold 10 extends through the full width of the cup body including the lower portion of the side flap extensions 6, 7, so that a strong, efficient handle portion is afforded, said handle fold also serving as reinforcing means for the cup body. The handle portion 10, as shown in Figure 4 normally projects away from the side of the cup to be conveniently gripped between the fingers. When the cups are nested the handle portion 10 folds against the adjoining side wall of the cup.

In Figures 6 and 7 of the drawings is illustrated one form of dispensing device adapted to dispense cups of the improved construction of the present invention. B designates the dispensing device and a designates the cups having the handle portions 10. The dispensing device B is in the form of a carton of substantially flat form provided with closure flaps b—b' at its ends, the carton being adapted to have the cups a introduced therein through the upper end thereof. The dispensing device B is provided near its lower end with yieldable cup supporting and separating means, shown in this instance, as comprising yieldable members c constructed of rubber or other suitable material, secured within the carton B at the sides thereof by suitable means, such as bolts and nuts 11, 12, as shown. As will be understood the yieldable members c are adapted to engage the angular side edges of the cups a, acting to support the stack of cups and providing for the withdrawal of the cups one by one from the dispensing device by a downward pull thereupon as the cups are successively presented in terminal position at the lower end of the dispenser.

It will be noted that by the particular construction hereinbefore set forth, a collapsible cup is provided in which the connections of the front and back walls are such as to prevent leakage, and efficient reinforcing means is provided, the resulting structure being of a satisfactory, efficient nature that can be produced at low cost. The handle portion of the cup formed by a transverse fold of a lower end section of the cup is of a strong, efficient character, the same being adapted to be conveniently gripped between the fingers and providing for readily withdrawing the cups singly from a dispenser, at the same time the handle fold serves as a transverse reinforce at the lower part of the cup and the structure is such as to not interfere with the nesting of the cups.

While a specific embodiment of the invention is illustrated in the drawings, it will of course be understood that changes and

variations may be made in the particular construction of cup shown as will appeal to those skilled in the art and falling within the scope of the appended claims without departing from the spirit of the invention, and of course any form of dispenser suitable for the purpose may be employed for dispensing the cup.

What I claim is:

1. A paper cup adapted to be nested with similar cups, and said cup having a lower marginal portion thereof folded laterally to extend to one side of the body of the cup and constituting a handle portion, and said handle portion lying flat against the adjoining side wall of the cup when the cup is nested within another cup.

2. A paper cup of substantially flat form adapted to be nested with similar cups in a stack, said cup being closed at its lower end and having a lower marginal portion thereof folded laterally to extend to one side of the body of the cup and constituting a handle portion, and adapted to lie flat against the adjoining side wall of the cup when the cup is nested within another cup.

3. A paper cup of substantially flat form having its lower marginal portion throughout its width folded laterally, said folded lower marginal portion forming a handle portion and serving to reinforce the cup body.

4. A drinking cup of substantially flat form made from a single blank folded transversely to form main front and back walls joined at their lower ends, and each of said front and back walls having integral opposing side flap extensions extending the full length of the front and back walls and joined together at their lower ends, said opposing flap extensions at either side of the blank being folded longitudinally one upon the other and upon one of the first mentioned walls, and the outermost of said opposing flap extensions being secured directly to one of the first mentioned walls.

5. A drinking cup of substantially flat form made from a single blank folded transversely to form main front and back walls joined at their lower ends, and each of said front and back walls having integral opposing side flap extensions extending the full length of the front and back walls and joined together at their lower ends, the flap extension of one of said walls being of greater width than the flap extension of the other wall, said flap extensions at either side of the blank being folded one upon the other and secured to one of the first mentioned walls, the flap extensions of greatest width overlapping and being secured by adhesive to the said wall and also to the other flap extensions.

6. A drinking cup of substantially flat form made from a single blank folded trans-

- versely to form main front and back walls joined at their lower ends, and each of said front and back walls having integral opposing side flap extensions extending the full length of said front and back walls and joined together at their lower ends, the flap extensions of one of said walls being of greater width than the flap extensions of the other wall, said flap extensions at either side of the blank being folded one upon the other and upon one of said first mentioned main walls and secured thereto, the flap extensions of greatest width overlapping and being secured by adhesive to the said main wall and also to the other flap extensions, and one of said main walls having a top flap extension folded back upon said wall and secured by adhesive thereto and to the lateral flap extensions of one of said first mentioned walls.
7. A drinking cup of substantially flat form made from a single blank folded transversely to provide main front and back walls of the cup joined together at their lower ends, said cup having its bottom marginal portion throughout the width thereof folded laterally, said folded bottom marginal portion forming a handle portion and serving to reinforce the cup body.
8. A drinking cup of substantially flat form made from a single blank folded transversely to form main front and back walls joined at their lower ends, and each of said front and back walls having integral opposing side flap extensions extending the full length of said front and back walls and joined together at their lower ends, said opposing side flap extensions at either side of the blank being folded one upon the other and upon and secured to one of the first mentioned walls, said cup having a lower marginal section thereof throughout the width of the same folded laterally, said folded lower marginal section forming a handle portion and serving to reinforce the cup body.

In testimony whereof I hereunto affix my signature.

WILLIAM A. RINGLER.
